UNITED STATES PATENT OFFICE.

GEORGE M. McCANN, OF NEW CASTLE, DELAWARE.

BREECH MECHANISM FOR GUNS.

Application filed January 15, 1926. Serial No. 81,549.

(GRANTED UNDER THE ACT OF MARCH 3, 1883, AS AMENDED APRIL 30, 1928, 370 O. G. 757.)

The invention described herein may be manufactured and used by or for the Government for governmental purposes without the payment to me of any royalty thereon.

6 This invention relates to a breech mechanism for guns.

In firing a gun at high elevations the operation of inserting the round of ammunition into the chamber is greatly facilitated when 10 the loader has a clear view of the entrance to the chamber. An important consideration which dictates the provision of such a feature in a breech mechanism is the element of safety obtained when handling 15 ammunitions equipped with a sensitive nose fuse. This facility in loading may be afforded by the use of a vertical or drop breech block wherein the upper part of the breech ring is cut away. However, a drop breech 20 block is not suitable to high angle firing by reason of clearances which would have to be provided and inherently because of the added mechanism required to raise the block to the closed position.

25 The principal object of this invention is to provide a breech mechanism combining all the advantages of the drop block with the simplicity of the sliding block.

Another important object is to provide a 30 latch mechanism which prevents the breech block from being closed on the hand of the loader and which is conveniently positioned to be tripped by the loader as his hand is withdrawn after ramming home the round.

35 A novel catch is provided which is adapted to hold the latch in both the raised and lowered position.

A still further object is to associate with the block a pivoted tray which is positioned 40 to support the round when the breech block is open.

To these and other ends, my invention consists in the construction, arrangement, and combination of elements, described hereinafter, and pointed out in the claims forming a part of this specification.

A practical embodiment of the invention is illustrated in the accompanying drawings, wherein:

50 Fig. 1 is a fragmentary plan view of a gun provided with a breech mechanism constructed in accordance with the invention;

Fig. 2 is a view in right side elevation thereof;

Fig. 3 is a view in rear elevation and partly in section with the breech block open and the latch in position prior to inserting the round;

Fig. 4 is a similar view showing the relation between the latch and the block at the moment when the round has been rammed home and the latch raised;

Fig. 5 is a sectional view through the breech ring taken on the line 5—5 of Fig. 1 and showing the position of the latch with the block closed;

Fig. 6 is a detail view in rear elevation of the latch;

Fig. 7 is a view in side elevation thereof;

Fig. 8 is a detail view in side elevation of the latch catch;

Fig. 9 is an end view thereof; and

Figs. 10 and 11 are detail views of the breech block tray.

Referring to the drawings by numerals of reference:

The breech ring 5 of a gun is transversely recessed to receive a sliding breech block 6 which is manually moved to its open and closed position by means of an operating lever 7 pivoted in the breech ring and having a cross head 8 working in a cam groove 9 in the upper face of the block. Pivoted to the block is a tray 10 having a pin 11 riding in a groove 12 in the breech ring during reciprocation of the block. When the block is open, the tray is dropped, as shown in Figures 3 and 4, so as to provide a rest for the shell as it is being inserted in the chamber. When the block is closed the tray is folded against the end of the block, as shown in Figure 5, so as not to project beyond the breech ring.

The breech ring is also provided with the usual circular loading aperture 13 to permit insertion of the round and, as in the typical drop block breech mechanism, the portion of the breech ring above this aperture is cut away to provide an opening 14 so that a clear view of the mouth of the chamber is afforded when the gun is in high elevation and also to permit the loader to carry his hand through to clear the piece after ramming in a round.

This arrangement is utilized to conveniently position a suitable latch mechanism which normally prevents the breech block from being closed on the hand of the loader and which may be tripped by the loader with perfect safety and without special effort. The mechanism shown in the drawings comprises a latch 15 formed with ribs 16 by which it is mounted in a groove cut 10 in the breech ring at the head of the opening 14. The ribs are irregularly terminated short of the bottom of the latch for a purpose which will appear hereinafter. The latch is normally depressed into the path 15 of the breech block by means of a spring 17 confined between the breech ring and a foot 18 on the latch while a finger grip 19 is provided on the upper end of the latch whereby it may be raised.

20 Mounted in the breech ring to the left of the latch is a spring pressed catch 20 whose end 21 is adapted to engage in a recess 15' in the latch (Fig. 4) to hold the same clear of the block after it has been manually 25 raised.

As the breech block is moved in closing a depending lug 22 on the catch enters a groove 23 in the upper face of the block and is brought up against the end of the groove 30 before the block arrives home, so that the final movement of the block serves to withdraw the catch from the recess 15' in the latch (Fig. 5) thereby permitting the latch to be depressed sufficiently by its spring to 35 prevent reentry of the catch in the recess 15'. The latch in this position rests upon the block and is subsequently enabled to assume its lowermost position when the block is open, as seen in Figure 3. In order to 40 limit the downward movement of the latch, one of its ribs 16 is adapted to contact the catch.

The breech mechanism includes a more or less conventional extractor 24 operating 45 in a well known manner and whose upper hub 25 is disposed in a cam groove 26 in the bottom of the block. As the round is inserted into the chamber its flange engages the lip 27 of the extractor and results in moving the block sufficiently to the left to prevent the round from falling out of the chamber. The movement of the block is limited by the latch and is in the position shown in Figure 4. Movement of the block to closed 55 position can not be completed unless the latch has been lifted by the loader.

In all operations of the breech mechanism there is no danger of the hand of the loader being struck by the block as his hand will be 60 clear of the block when raising the latch.

While in the foregoing there has been illustrated and described such combination and arrangement of elements as constitute the preferred embodiment of my invention, 65 it is nevertheless desired to emphasize the

fact that interpretation of the invention should only be conclusive when made in the light of the subjoined claims.

I claim:

1. A gun, a breech ring thereon having an aperture for inserting a round of ammunition and an opening in the top of the ring connecting with said aperture, a sliding breech block, means for opening and closing the block, a tray pivoted to a lower edge 75 of the block and adapted to form a rest for the round when the block is open, means whereby the tray is folded against the block as the block is closed, a latch having a short rib and a recess mounted in the ring at the head of the opening and normally moved into the path of the block to prevent its closing, said latch adapted to be manually lifted by the loader in withdrawing his hand after inserting a round, a spring 85 pressed catch adapted to enter the recess in the latch when the latch is in the raised position and to engage the rib when the latch is in the lowered position, and a depending lug on the catch adapted to be 90 struck by the block in closing to withdraw the catch from the recess in the latch.

2. A gun, a breech ring thereon, having an aperture for inserting a round of ammunition and an opening in the top of the ring 95 connecting with said aperture, a sliding breech block, means for opening and closing the block, a latch having a short rib and a recess mounted in the ring at the head of the opening and normally moved into the path 100 of the block to prevent its closing, said latch adapted to be manually lifted by the loader in withdrawing his hand after inserting a round, a spring pressed catch adapted to enter the recess in the latch when the latch 105 is in the raised position and to engage the rib when the latch is in the lowered position, and a depending lug on the catch adapted to be struck by the block in closing to withdraw the catch from the recess in 110 the latch.

3. A gun, a breech ring thereon, having an aperture for inserting a round of ammunition and an opening in the top of the ring connecting with said aperture, a sliding breech block, means for opening and closing the block, a latch mounted in the ring at the head of the opening and normally moved 115 into the path of the block to prevent its closing, said latch adapted to be manually lifted by the loader in withdrawing his hand after inserting a round, a spring pressed catch adapted to retain the latch in both its lowered and raised position, and a depending lug on the catch whereby the 120 same may be operated by the block in closing.

4. A gun, a breech ring thereon having a loading aperture and an opening in the top 125 of the ring connecting with said aperture, a

- sliding breech block, a latch mounted in the ring at the head of the opening and normally moved into the path of the breech block to prevent its closing, said latch 5 adapted to be manually raised to clear the block, and means releasable by the block for holding the latch in the raised position.
5. A gun, a breech ring thereon having a loading aperture and an opening in the top 10 of the ring connecting with said aperture, a sliding breech block, a latch mounted in the ring and normally moved into the path of the breech block to prevent its closing, said latch adapted to be manually raised to clear the block, and means for releasably holding 15 the latch in the raised position.
6. A gun, a breech ring thereon having a loading aperture and an opening in the top of the ring connecting with said aperture, a sliding breech block, a tray pivoted to the 20 block and adapted to form a rest for the round when the block is open and means whereby the tray is folded against the block as the block is closed.

GEORGE M. McCANN.
